(57) **CLAIM**

The ornamental design for a loudspeaker, as shown and described.

DESCRIPTION

FIG. 1 is a top perspective view of a loudspeaker showing our new design;

FIG. 2 is a front elevational view thereof;

FIG. 3 is a right side elevational view thereof, the left side being a mirror image;

FIG. 4 is a rear elevational view thereof;

FIG. 5 is a top plan view thereof; and

FIG. 6 is a bottom plan view thereof.

FIG. 7 is a top perspective view of a loudspeaker showing an alternative embodiment of our new design.

FIG. 8 is a front elevational view thereof;

FIG. 9 is a right side elevational view thereof, the left side being a mirror image;

FIG. 10 is a rear elevational view thereof;

FIG. 11 is a top plan view thereof; and,

FIG. 12 is a bottom plan view thereof.

The broken lines in FIGS. 1–12 represent the bounds of the claimed design; the region within these broken lines forms no part of our claimed design.
